UNITED STATES PATENT OFFICE.

EDWIN A. WEBSTER, OF GROVELAND, MASSACHUSETTS, ASSIGNOR TO HAVERHILL SHOE MACHINERY COMPANY, OF HAVERHILL, MASSACHUSETTS, A CORPORATION OF MAINE.

HEEL-BREASTING MACHINE.

1,133,240.

Specification of Letters Patent.

Patented Mar. 23, 1915.

Application filed May 8, 1911. Serial No. 625,752.

To all whom it may concern:

Be it known that I, EDWIN A. WEBSTER, a citizen of the United States, residing at Groveland, in the county of Essex and 5 State of Massachusetts, have invented an Improvement in Heel-Breasting Machines, of which the following is a specification.

This invention relates to certain improvements in heel-breasting machines, particularly applicable to that type of machines in which a depending breasting-knife is provided, and either the jack, or the knife is moved vertically, to perform the breasting operation, and in which the jack is also 15 adapted to be moved forwardly, so that the shoe may be placed thereon, and may then be moved rearwardly into breasting position.

In order that the requirements of the 20 trade may be met, it is necessary that the breast of the heel be straight, and if it is not cut straight by the breasting-knife it must be made so on the heel-scouring machine.

25 In breasting machines of the type above referred to, whether the knife is made to reciprocate laterally, as in the machine of my prior Patent #981,506, dated January 10, 1911, or is held stationary laterally, as 30 is customary in other machines, it is necessary to bevel the knife almost wholly on the front side, or side next the chip, and this unequal bevel strongly tends to cause the knife to be deflected from a straight course 35 into the heel and cut the breast on an inward slant, or curve, the thicker the chip which is removed, the greater being the tendency of the knife to run inward, and this tendency generally being the greatest when the 40 knife is close to the shank, as the chip is usually thickest at this point. As the knife is held from moving laterally rearward, the result of this tendency, therefore, is to cause the shoe, and consequently the jack on which 45 it is supported, to be moved forwardly, or toward the operator, and, in machines previously employed, the operator usually attempts to prevent this movement by pressing rearwardly on the shoe or jack. Inasmuch as the force with which the shoe, or jack 50 is pressed forwardly by the knife is usually greater than any counteracting force which

may be exerted by the operator, the result is that heels are frequently breastested imperfectly in the manner above described. Moreover, if the operator presses the jack rearwardly with too much force, he is likely to force the jack back beyond the breasting position, which would also be objectionable. The result secured in this particular, thus, 55 to a large extent, depends on the ability of the operator to hold the shoe in the desired position. The tendency of the knife to be deflected into the heel, as before described, also tends to throw the toe of the shoe or 60 last upwardly, and it frequently happens that the shoe is thrown upwardly to such an extent that it is pulled from the jack, thus not only causing serious delay and difficulty, but also frequently causing the heel to 65 be damaged to such an extent that a new heel must be applied.

As it is frequently necessary to adjust the jack to different positions for different styles of shoes, the utmost freedom and facility 75 of adjustment of the jack is necessary at the time it is brought into breasting position, as the operation must be rapidly performed.

The object of my invention is to provide 80 a breasting machine of the above described type with means whereby the utmost facility of adjustment of the jack is permitted, to bring the shoe into breasting position, and in connection therewith, to provide means for preventing the jack from moving horizontally during the breasting operation, so that, as the operation is performed the shoe cannot be moved out of position by the knife, and the knife will be 85 caused to cut the breast perfectly straight, so that there will be no necessity of straightening the heel-breast by a subsequent operation. I accomplish this object by providing means for automatically locking the jack 90 against horizontal movement at the beginning of the breasting operation, and for holding it in locked position until said operation is finished, the jack being unlocked 95 on the return movement.

100 For a complete understanding of my invention reference is made to the accompanying drawings, in which:—

Figure 1 is a side elevation of a heel-breast-

ing machine made according to my invention. Fig. 2 is a rear view of the breeding mechanism of the machine on an enlarged scale, and partly in section on line 2—2 of Fig. 1. Fig. 3 is a similar view showing the parts in a different position, and, Fig. 4 is a detail view of the locking device.

As shown in the drawing, the base *a* is provided with a head *b*, in which the pending breeding-knife *c*, which is reciprocated as described in my said prior patent, is mounted, and a heel holder *d*, is provided to hold the heel from tipping or vibrating laterally, and is mounted to move vertically on the rods *e*, as also described in my said prior patent.

The jack *f*, shown, is of a form which is especially adapted for breeding the shoe while on the last, but the particular form of jack employed is not material.

A slide, or carrier, *g*, is mounted to move vertically in the frame and the jack *f* is mounted on an arm *h*, arranged to swing forwardly and rearwardly on a pivot *i* secured in the slide *g*, so as to carry the jack horizontally into and out of breeding position, in the well-known manner.

The arm *h* is provided at one side with a longitudinally curved T-shaped head or projection *h'*, which is adapted to move in a groove or slot formed in a thickened portion of the slide *g*, at its upper end, both the projection and groove being curved on an arc having the pivot *i* as its center.

An operating-lever *j* is mounted on a pivot *k*, supported by a bracket *k'* on the base, said lever *j* being provided with an extensible end portion *j'* having a straight face *j²* extending nearly at right angles thereto and another straight face *j³* arranged at a slightly obtuse angle with relation to said face *j²*. The main portion of the lever *j* beneath its pivot is also provided with a straight face *j⁴* arranged parallel to the face *j³*, and an engaging end portion *j⁵*.

A locking pin *m* is mounted to move longitudinally in the thickened upper end portion of the slide *g*, and at right angles thereto, so that it may enter the T-shaped groove *g'* therein, and its end may engage the adjacent face of the head *h'*, and a vertical shaft *n*, having a cam *n'* on its lower end, is rotatably mounted in the slide, said cam being arranged to engage the pin *m* and move the same into engagement with the head *h'*, when said shaft is rotated, to lock the arm *h* against swinging movement. The shaft *n* has a finger *o* which extends horizontally from the upper end thereof in position to be engaged by the lower end portion *j⁵* of the lever *j*, so that when said lever *j* is swung on its pivot toward the finger *o*, the shaft *n* will be rotated to move the pin *m* to locking position. A spring *q* acts to move the lever *j* away from finger *o*.

A friction roll *s* is mounted on the heel-holder *d*, said roll being arranged to engage the upper end portion of the lever extension *j'*, and the spring *q* acting to hold said extension constantly against said roll.

The slide *g* is adapted to be lifted by the treadle *t* and the connected link and lever mechanism shown, as in said prior patent.

The operation of the above described device is as follows: The operator swings the jack forwardly on its pivot *i* and adjusts the shoe thereto, and then moves the jack back into breeding position. He then depresses the treadle causing the slide *g* to be raised and bringing the heel up into engagement with the holder *d* and breeding-knife *c* successively, as shown in Fig. 2. The holder *d* is lifted with the jack, during the entire upward movement of the jack after the heel engages the holder, and, as said holder begins to move upward the roll *s* thereon will be forced against the face *j²* of the lever extension *j'*, and will immediately cause the lever *j* to be swung sufficiently to cause its end portion *j⁵* to engage finger *o* and rotate the shaft *n* to move the locking pin *m* into locking engagement with the head *h'*, as shown in Fig. 3, so that the jack is positively held against swinging movement. When the lever *j* is in locking position, its faces *j³* and *j⁴* will be vertical, so that, during the further upward movement of the holder *d'*, the parts will be held in locked position, without obstructing the upward movement of the jack. As the jack is lowered the opposite movement will take place, permitting the spring *q* to swing the lever *j* out of engagement with finger *o*, so as to unlock the jack, and permit it to be swung forward.

It will thus be seen that the means for locking and unlocking the jack in no way interferes with the normal operation of the machine, as the jack is not locked until the shoe is actually lifted to the breeding-knife and is unlocked at the end of the return movement.

I claim:—

1. In a heel-breasting machine, two operating members comprising a breeding-knife and a jack, said jack being movable horizontally to and from breeding position, a treadle for vertically reciprocating one of said members to perform the breeding operation and a locking device disposed to be actuated by such member during an initial portion of the acting movement thereof to lock the jack against horizontal movement, and means to move said device to unlocked position on the return movement thereof, substantially as described.

2. In a heel-breasting machine, two operating members comprising a breeding-knife and a jack, said jack being movable horizontally to and from breeding posi-

tion, a treadle for vertically reciprocating one of said members to perform the breast-
ing operation, and an independent locking device disposed to be actuated during the initial portion of the acting movement of said vertically reciprocating member to lock said jack against horizontal movement and to hold it locked during the latter part of the acting movement, substantially as de-
scribed.

3. In a heel-breasting machine, a depend-
ing breasting-knife, a jack movable hori-
zontally into breasting position beneath the
knife and having means for moving the
same vertically to perform the breasting
operation, a locking device for holding the
jack against horizontal movement when in
breasting position, and means to move said
locking device to locking position actuated
by the jack during the initial portion of its
lifting movement, substantially as de-
scribed.

4. In a heel-breasting machine, a depend-
ing breasting-knife, a jack movable hori-
zontally into breasting position beneath the
knife and having means for moving the
same vertically to perform the breasting
operation, and a locking device, disposed
to be actuated by a vertical movement of
the jack, for holding the jack against hori-
zontal movement, substantially as described.

5. In a heel-breasting machine, a depend-
ing breasting-knife, a jack movable hori-
zontally into breasting position beneath the
knife, and having means for moving the
same vertically to perform the breasting
operation, and a locking device disposed
to be actuated by the jack during the initial
portion of its upward movement to
lock the jack against horizontal movement
and to hold it locked during the latter part
of the upward movement, substantially as
described.

6. In a heel-breasting machine, a depend-
ing breasting-knife, a jack movable hori-
zontally into breasting position beneath the
knife, a locking device for holding the jack
in said position, and means for simultane-
ously lifting the jack to perform the breast-
ing operation and for moving said locking
device to operative position, substantially
as described.

7. In a heel-breasting machine, a depend-
ing breasting-knife, a jack movable hori-
zontally into breasting position beneath the
knife, a locking device for holding the jack
in said position, an operating lever for said
locking device, and means, actuated by the
jack during the initial portion of its lift-
ing movement, for operatively moving said
lever and for holding said lever in opera-
tive position during the subsequent por-

tion of said lifting movement, substantially
as described.

8. In a heel-breasting machine, a depend-
ing breasting-knife, a jack movable hori-
zontally into breasting position beneath the
knife, a vertically movable carrier, on
which said jack is mounted, a locking de-
vice mounted on said carrier, lifting means
for said carrier, and means actuated by
said carrier when it is lifted for moving
said locking device to lock the jack in breast-
ing position, substantially as described.

9. In a heel-breasting machine, a depend-
ing breasting-knife, a jack movable hori-
zontally into breasting position beneath the
knife, and having means for moving the
same vertically to perform the breasting
operation, a locking device movable with
the jack for holding the jack in breasting
position, a lever mounted independently of
the jack, a heel-holder vertically movable
with the jack, and means carried by said
holder for moving said lever to move said
locking device to lock the jack, substan-
tially as described.

10. In a heel-breasting machine, two
operating-members comprising a breasting-
knife and a jack, said jack being movable
horizontally to and from breasting posi-
tion, means for vertically reciprocating one
of said members to perform the breasting
operation, a heel-engaging device disposed
adjacent the cutting edge of said knife in
position to engage the heel approximately
at the time it is engaged by the knife, means
permitting said engaging device to yield
vertically with relation to the knife, and
means, operated by said engaging device,
as it yields, for locking the jack against
horizontal movement, substantially as de-
scribed.

11. In a heel-breasting machine, a de-
pending breasting-knife, a jack movable
horizontally into breasting position beneath
the knife and having means for moving the
same vertically to perform the breasting
operation, a vertically movable heel-engag-
ing device disposed adjacent the cutting
edge of said knife in position to be en-
gaged and lifted by the heel approximately
at the time the heel is moved into engage-
ment with said edge, and means operated
by said engaging device as it is lifted for
locking the jack against horizontal move-
ment, substantially as described.

In testimony whereof, I have signed my
name to this specification, in the presence
of two subscribing witnesses.

EDWIN A. WEBSTER.
